UNITED STATES PATENT OFFICE.

HANS HANSEN, OF NEW ROCKFORD, NORTH DAKOTA.

ADJUSTABLE FOOTBOARD FOR WAGONS.

1,182,169.

Specification of Letters Patent.

Patented May 9, 1916.

Application filed April 1, 1915. Serial No. 18,554.

To all whom it may concern:

Be it known that I, HANS HANSEN, a citizen of the United States, residing at New Rockford, in the county of Eddy and State of North Dakota, have invented certain new and useful Improvements in Adjustable Footboards for Wagons, of which the following is a specification, reference being had to the accompanying drawings.

10 This invention relates to an improved adjustable foot-board for wagons and has for its primary object to provide a foot-board which may be easily and quickly applied to either section of a double wagon box.

The invention has for one of its important detail objects to provide improved means for vertically adjusting the foot-board with respect to the wagon box and 20 also disposing said board in inoperative position.

The invention has for an additional object to provide sectional adjustable hangers adapted for application to the vertical end 25 wall of the wagon box, a foot-board hingedly mounted upon said hangers a flexible element connected to the hangers and adapted to support the foot-board in a horizontal position.

30 With the above and other objects in view my invention consists in the novel features of construction, combination and arrangement of parts to be hereinafter more fully described, claimed and illustrated in the accompanying drawings in which—

Figure 1 is a longitudinal section through a double wagon body showing one application of my improved foot-board thereto. Fig. 2 is a fragmentary section similar to 40 Fig. 1 showing another application of the board and the same disposed in its lowered position. Fig. 3 is a detailed fragmentary perspective view of the foot-board.

Referring in detail to the accompanying drawing, wherein like reference numerals are indicative of similar parts, 5 designates the lower or body section of a wagon box and 6 the upper removable section thereof. To 50 the side walls of this upper box, section 6, the vertically disposed cleats 7 are secured upon the inner and outer faces thereof and project below the lower edges of said walls. The projecting ends of the respective cleats are adapted for frictional binding engagement upon the corresponding faces of the side walls of the body section 5 of the

wagon. The present invention is not, however, to be limited to this particular mounting of the upper box section 6, as various other means for removably mounting the same upon the box section 5 may be employed.

The present invention includes a pair of hangers or brackets each of which consists of two sections indicated by the numerals 65 8 and 9 respectively, the former being provided with a hook 10 on one end. Each of the hanger sections is formed with two or more openings therein to receive the connecting bolt 12, and it will be readily understood that the hanger section 8 may be longitudinally adjusted upon the section 9, and the bolt 12 inserted through coinciding openings so as to rigidly hold the bracket section 8 in its adjusted position with respect to the section 9. Upon the lower ends of the hanger sections 9 the footboard 13 is mounted by means of the hinges 14. Adjacent to the free longitudinal edge of the foot-board and at each end thereof 70 hooks 15 are provided to which the free ends of chains 16 are adapted to be connected, the other ends of said chains being suitably attached to the bracket sections 9 of the hangers.

As clearly shown in Figs. 1 and 2 of the drawing; the hooked terminals 10 of the bracket sections 8 are adapted to be engaged upon the upper edge of the end wall of either the body section 5 of the wagon box, or the upper removable section 6 thereof. During the loading of the wagon, the chains 16 are disconnected from the brackets so that the foot-board 14 will drop downwardly and hang below the hangers 95 upon which it is mounted. Thus there will be no interference by the foot-board with the loading of the material into the wagon body. When the contents of the wagon body have been dumped or unloaded the 100 foot-board is raised to a horizontal position as in Fig. 1 and the free ends of the chains 16 connected to the bracket sections 8. The board is now in position for use. By the provision of the adjustable hangers 105 the foot-board may be raised or lowered to the desired position to suit the convenience of the individual. If desired, the terminal hooks 10 of the adjustable hanger sections may be provided with suitable 110 clamps for engagement with the end wall of the wagon body.

From the foregoing description taken in connection with the accompanying drawing, the construction, manner of use, and several advantages of my invention will be clearly understood, and it will be seen that I have produced a highly convenient and serviceable adjustable foot-board which is readily attachable to either the single or double type of wagon body without necessitating any material alterations in the construction thereof. The board may be easily and quickly released so that it will swing downwardly to an inoperative position where it is out of the way and will not provide an obstruction to the proper loading of the vehicle. The mounting and supporting means for the foot-board, while of very simple construction is nevertheless extremely durable and serviceable. Owing to the simplicity of the device it will be appreciated that the same may be produced at small manufacturing cost.

While I have shown and described the preferred construction and arrangement of the several parts, it is nevertheless to be understood that the invention is susceptible of considerable modification therein, and I therefore reserve the privilege of resorting to all such legitimate changes as may

be fairly embodied within the spirit and scope of the invention as claimed.

What I claim is:

The combination with a wagon box, of a detachable interior foot board for the wagon box including the foot board proper, hanger sections hingedly connected at one of their ends to one longitudinal edge of the foot board adjacent to the opposite ends thereof, additional hanger sections adapted for detachable engagement over the upper edge of one of the box walls, means for adjustably connecting the hanger sections on the foot board to the latter hanger sections, and chains connected at one of their ends to the foot board adjacent its other longitudinal edge, said board normally hanging in a pendant position in parallel relation to the box wall, said chains being adapted to be attached at their free ends to the latter hanger sections to support the foot board in a horizontal position.

In testimony whereof I hereunto affix my signature in the presence of two witnesses.

HANS HANSEN.
